UNITED STATES PATENT OFFICE.

JOHN T. PRICE, OF ELLSTON, IOWA.

SLIDING BED.

1,232,602.

Specification of Letters Patent. Patented July 10, 1917.

Application filed October 23, 1915. Serial No. 57,561.

To all whom it may concern:

Be it known that I, JOHN T. PRICE, a citizen of the United States, residing at Ellston, in the county of Ringgold and State of Iowa, have invented certain new and useful Improvements in Sliding Beds; and I do hereby declare the following to be a full, clear, and exact description of the invention, such as will enable others skilled in the art 10 to which it appertains to make and use the same.

The invention relates to improvements in beds.

The object of the present invention is to 15 improve the construction of beds and to provide a simple, practical, and comparatively inexpensive bed designed for the use of persons having tuberculosis, weak lungs or desiring for any other reason to sleep 20 outdoors and equipped with means for enabling it to be readily moved from the interior of a room or apartment to the exterior of the house without necessitating a 25 person leaving the bed while such change in position of the same is being made.

With these and other objects in view the invention consists in the construction and novel combination and arrangement of parts hereinafter fully described, illustrated in 30 the accompanying drawings and pointed out in the claims hereto appended, it being understood that various changes in the form, proportion and minor details of construction may be resorted to without departing 35 from the spirit or sacrificing any of the advantages of the invention.

In the drawings

Figure 1 is a side elevation partly in section showing a sliding bed constructed in accordance with this invention,

Fig. 2 is an end elevation of the same,

Fig. 3 is a transverse sectional view on the line 3—3 of Fig. 1,

Fig. 4 is a detail sectional view illustrating the manner of mounting the legs of the bed on the rails,

Fig. 5 is a detail sectional view on the line 5—5 of Fig. 1.

Like numerals of reference designate corresponding parts in the several figures of the drawings.

In the accompanying drawings in which is illustrated the preferred embodiment of the invention, 1 designates a bed designed to 55 slide through an opening 2 in a wall 3 for arranging it either interiorly of the room

or exteriorly of the wall and provided at its inner and outer ends with heads or closures 4 and 5 adapted to fit in the opening 2 and close the same when the bed is in either position. The closures are provided with flanges 6 projecting beyond the opening 2 and adapted to cover the same. The opening may be formed directly in the wall as indicated in Fig. 1 of the accompanying drawings or the bed may be projected through a door or window on to a porch as will be readily understood.

The bed is provided at the bottom with a plate 7 of sheet metal entirely closing the 70 bottom of the bed and adapted to exclude the air and the sides of the bed are also provided with sheet metal guards 8 extending a sufficient distance above the bed clothing, not shown to exclude snow and the like from 75 the same at the inner faces of the side rails of the bed but the bed may be constructed of any other suitable material as will be readily understood.

The bed is supported at the corners by 80 legs 9 and 10 arranged interiorly and exteriorly of the house or other building and adjustably secured to the ends or closures 4 and 5, by clamps 11 consisting of blocks or plates of metal provided with openings 12 85 to receive the legs which are engaged by set screws 13. The clamps which are arranged in pairs have attaching portions 14 screwed or otherwise secured to the heads or closures 4 and 5. The legs are provided at their 90 lower ends with horizontal pivots or spindles 15 on which are mounted wheels 16 preferably provided with rubber tires 17 and having anti-friction bearings 18 which may be ball bearings, roller bearings or the 95 like to reduce the friction to a minimum. The wheels are arranged upon rails 19 preferably constructed of angle iron and consisting of two sides or wings, one side or wing being arranged horizontally to form 100 the tread of the rail and the other extending vertically at the outer side of the tread as clearly illustrated in Fig. 4 of the drawings. The rails 19 which project exteriorly from the wall 3 and which are supported by inclined braces 20 are arranged at the floor level and they may have inner extensions 21 arranged on the floor 22 as shown in Fig. 1 of the drawings.

The rails enable the bed to be readily 110 moved to a position interiorly or exteriorly of a house and this may be effected without

the person occupying the bed leaving his or her position within the same. This will enable a person to dress in a warm room, get into the bed and after having the covers 5 properly arranged be moved to a position outdoors.

The bed may be moved inwardly and outwardly by a nurse or by the occupant and in order to enable this to be accomplished 10 the bed is equipped with a rope 23 or other flexible connection secured at its terminals to the wall 2 at the top of the opening at 24 and arranged on pulleys 25 at the heads or 15 closures 4 and 5. The rope forms an endless flexible connection and will enable the bed to be moved back and forth along the track. The braces 20 are secured at their outer ends to the outer ends of the rails and they extend downwardly and inwardly to the 20 wall 3. The adjustable connection between the legs and the bed or body of the bed enable the latter to be raised and lowered to arrange the parts properly with relation to an opening in a wall.

25 What is claimed is:—

1. The combination with a wall having an opening, of a bed slideable through the opening and provided with head and foot

pieces forming closures for the opening, said head and foot pieces being tapered to snugly 30 fit the openings to form a tight joint and a support for one end of the bed, flanges carried by the outer faces of said head and foot pieces and adapted to extend beyond the opening for covering the same and for engaging the edges of the opening to limit the inward and outward movement of the bed, said bed being provided with legs on the head and foot pieces arranged interiorly and exteriorly of the wall for supporting one 35 40 end of the bed opposite the wall.

2. The combination with a wall having an opening, of a bed slideable through the opening, and provided with a plate completely 45 inclosing the bottom of the bed, side walls formed on said plate, head and foot pieces connected to said plate and side walls, said head and foot pieces forming closures for said opening, and means to limit the inward and outward movement of said bed.

In testimony whereof I affix my signature in presence of two witnesses.

JOHN T. PRICE.
